NEW JERSEY.

DESIGN FOR A BAG-FRAME.

40,648.

Specification for Design.

Patented Apr. 19, 1910.

Application filed January 20, 1910. Serial No. 539,204. Term of patent 3½ years.

To all whom it may concern:

Be it known that we, CHRISTIAN HIERING and ALBERT FULLER, citizens of the United States, residing in the city of Newark, county of Essex, and State of New Jersey, have invented a new, original, and ornamental Design for Bag-Frames; and we do hereby declare the following to be a full, clear, and exact description of the invention, such as will enable others skilled in the art to which it appertains to make and use the same, reference being had to the accompanying drawings, and to letters of reference thereon, which form a part of this specification.

Figure 1 is a front elevation of a bag frame embodying our new design; and Fig. 2 is a plan view of the same.

As shown in the drawings, the leading or material feature of our design, consists in an ornamental bag frame having on its front, a series of embossed panels.

In said drawings, *a* and *a'* indicate a pair of ornamental frame sections which are pivotally secured at their outer end portions by rivets *b*. Each of said frame sections as *a*, is provided in its main body portion *c* with the panels *d*, and *d'*, and the hinge members *e* and *e'* of said frame section are provided with the panels *f* and *f'*. The panels are oblong in shape, and of such a width that the longitudinal edges of said panels project below and inside of the inside edge of the frame member. The inside corners of the panels are made angular as shown.

We claim:

The ornamental design for a bag frame, as shown and described.

CHRISTIAN HIERING.
ALBERT FULLER.
